UNITED STATES PATENT OFFICE.

FRANK M. MARSHALL, OF LOS ANGELES, CALIFORNIA.

WALL-PLUG.

No. 927,367.

Specification of Letters Patent.

Patented July 6, 1909.

Application filed June 19, 1907. Serial No. 379,737.

To all whom it may concern:

Be it known that I, FRANK M. MARSHALL, a citizen of the United States, residing at Los Angeles, in the county of Los Angeles and 5 State of California, have invented new and useful Improvements in Wall-Plugs, of which the following is a specification.

My invention relates to a metallic wall plug used for supporting insulators, screw 10 eyes or other securing means which are attached to the walls of buildings and to which telephone, telegraph or other electric transmission wires are strung or secured; and an object thereof is to provide a metallic plug 15 which may be readily inserted in the joints formed in a brick wall and which will be impossible to remove when once inserted except by extraordinary methods. I accomplish this object by means of the device described herein and illustrated in the accompanying drawings in which:—

Figure 1.—is a perspective view of my improved wall plug. Fig. 2.—is a longitudinal section of the same showing it in position in 25 a brick wall. Fig. 3.—is a cross section taken on line 3—3 of Fig. 1. Fig. 4.—is a view showing the cross section shown in Fig. 3 when the plug is in place in the wall. Fig. 5.—is a cross section illustrating a modified 30 form of plug.

Heretofore in attaching or securing insulators, screw eyes or other attaching means to the walls of brick or stone buildings preparatory to stringing electric transmission 35 or other wires, the mortar or cement has to be first removed before inserting the wooden plugs. This method of inserting plugs has consumed a great deal of time and the plugs after insertion have often become loosened 40 by crumbling of the mortar occasioned by dampness, thus necessitating frequent repairs. By the use of my improved device all danger arising from plugs becoming detached from the walls of brick buildings is obviated 45 and I am enabled to insert them in the minimum amount of time.

Referring to the drawings 5 designates a plug preferably formed of a resilient material such as thin sheet steel, comprising a blade 6, 50 preferably segmental in cross section, and a shank or head 7 struck by dies from a single piece of material. Blade 6 is preferably provided with serrated or toothed edges 8 the

points of the teeth extending forwardly toward the head or shank 7 and which are 55 adapted to grip the face of the brick work when the plug is inserted and prevent its withdrawal therefrom. The blade is preferably pointed as at 9 so as to facilitate its insertion. Shank 7 is illustrated as cylindrical in form though other forms may be used equally as well, and is filled with a soft material preferably lead or wood in which a bore 10 is provided slightly smaller in diameter than the screw to be inserted so that the 60 screw will cut threads in the soft material.

In securing the plugs in brick or other walls it is driven into the mortar or cement 11 between the bricks 12 as best shown in Fig 12, the shank or head 7 projecting beyond the 70 face of the wall as shown in full lines when a screw eye 13 is to be used to support the wires (not shown), or driven flush when as shown in dotted lines when a porcelain insulator is to be used, the wires in either case 75 being held at approximately the same distance from the wall.

In Fig. 5 I have illustrated a modified form of blade that may be used in lieu of the preferred form as illustrated in the preceding figures of the drawing.

It will be observed from the above construction that I have provided a wall plug that is easily inserted in a brick or other jointed wall and one whose shape will insure 85 it against withdrawal under ordinary conditions. It will be further noted by reference to Figs. 3 and 4 that the segmental form and resiliency of the blade 6 further increases its tendency against withdrawal. 90

Having described my invention what I claim as new and desire to secure by Letters Patent is:—

1. A wall plug comprising, a resilient spoon shaped blade, a cylindrical shank integral with said blade, a hollow core carried in said shank and means for engaging said core. 95

2. A wall plug comprising, a spoon shaped blade, a cylindrical shank integral with said blade, the distance between the edges of said 100 blade being greater than the diameter of said cylindrical shank, a core of soft material carried by said shank, and attaching means adapted to coöperate with said core.

3. A wall plug comprising, a spoon shaped 105 blade having serrations on the edges thereof,

a cylindrical shank formed integral with said blade, the distance between the edges of said blade being greater than the diameter of said cylindrical shank, a core of soft material carried by said shank, and attaching means adapted to coöperate with said core, substantially as described.

In witness that I claim the foregoing I have hereunto subscribed my name this 12 day of June, 1907.

FRANK M. MARSHALL.
